Attorney.

UNITED STATES PATENT OFFICE.

ADOLPH M. DEUTSCH, OF NEW YORK, N. Y.

PERMANENT COLLAR BUTTON.

1,412,045.

Specification of Letters Patent. Patented Apr. 11, 1922.

Application filed April 19, 1921. Serial No. 462,500.

To all whom it may concern:

Be it known that I, ADOLPH M. DEUTSCH, a citizen of the United States, residing at New York, in the county and State of New York, have invented certain new and useful Improvements in Permanent Collar Buttons, of which the following is a full, clear, and exact specification.

This invention relates to collar buttons and has for its object to provide a button which may be permanently attached to the neck band of a shirt, and is of such construction as will not be injured during the laundering of the shirt.

The invention contemplates the provision of a base plate, adapted to be sewed or otherwise permanently attached to a garment, and a button member having a shank which is hinged to said base plate so that it may be folded down into the plane thereof during the laundering process. Other objects will appear as the description proceeds.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:—

Figure 1 is a perspective view of the neck band of a shirt, showing a collar button constructed substantially in accordance with this invention and attached to the back of said band.

Figure 2 is a central vertical section through the base plate of the collar button drawn to a larger scale and showing the button proper in projected position as when in use, the folded position of said button being indicated in dotted lines.

Figure 3 is a detailed plan view of the blank from which the button and shank are formed, and

Figure 4 is a detailed view of a modified form of button blank.

The base plate 1 is preferably formed of metal stamped to substantially the shape illustrated in Figure 1 with a notch 2 in its lower edge and a slot 3 extending along the upper end of said notch and spaced therefrom by an uncut strip or bridge member 4. Around the margin of said base plate a reinforcing bead or corrugation 5 is formed in the stamping process, and suitable per-

forations 6 are made in the plate at the same time for sewing or otherwise attaching said plate to the neck band 7, as shown in Figure 1. The button 8 has its shank 9 hinged to the base plate by means of a tongue 10 which is bent around the strip or bridge member 4 and extends through the slot 3, as best shown in Figure 2, so that said button may be folded down in the notch 2, as indicated in dotted lines in Figure 2, to lie within the plane of the base plate and be protected during laundering by the bead or corrugation 5 and the material of the neck band 7.

The button and shank or preferably formed integrally from a sheet metal blank substantially of the contour illustrated in Figure 3. Said shank has a broad portion 11 arranged between the tongue 10 and the reduced shank portion adjacent the button 8, said broad portion 11 fitting in the notch 2 of the base plate and having lugs 13 at its inner end on opposite sides of the tongue 10 to form an abutment against the bridge member 4 to limit the upward movement of the button, as shown in Figure 2, said lugs being bent slightly upward at an inclination to the plane of the shank for this purpose. The button 8 is preferably formed of two complementary portions 14 and 15 which are integral with each other and with the shank 12, as shown in Figure 3. Each of said button portions 14 and 15 is pressed into semi-spherical shape by suitable dies or other means, not shown, and the portion 15 is subsequently bent over upon the portion 14, also preferably by suitable dies, so as to form the complete sphere or ball 8 shown in Figure 2. It will be noted that in Figure 3 the complementary portions of the ball extend in line 95 with the shank of the blank. As illustrated in Figure 4, complementary ball portions 16 and 17 may be arranged at opposite sides of the shank 18 so that one of said portions may be bent over upon the other to form the complete ball in substantially the same manner as already described in connection with the form of blank shown in Figure 3.

While the collar button has been shown and described as applied to the neck band of a shirt, it will be understood that it may also be used elsewhere and on other garments with good results.

I claim:

1. In a collar button, the combination with a base plate having a notch in one edge and a slot spaced from the end of said notch leav-

ing a bridge member between them, of a button having a shank hinged to said bridge member and adapted to fold into said notch, and a stop on said shank to engage said 5 bridge member for limiting the outward movement of the button.

2. In a collar button, the combination with a base plate having a notch in its edge and a slot spaced from the end of said notch 10 leaving a bridge member between them, of a button having a shank hinged to said bridge member and adapted to fold into said notch, said shank having a tongue at its inner end bent around said bridge member and 15 through said slot to form the hinge con-

nection, and lugs at the sides of said tongue to engage said bridge member for limiting the outward movement of the button.

3. In a collar button, the combination with a base plate having a notch in its edge, there 20 being a corrugation formed around the edge of said plate, of a button having a shank hinged to the plate at the upper end of said notch and adapted to fold into the latter with the button in the plane of said corrugation for the purpose specified. 25

In testimony whereof I have signed my name to this specification.

ADOLPH M. DEUTSCH.
